CLAIM

The ornamental design for a double hung head extrusion for windows, as shown and described.

DESCRIPTION

FIG. 1 is an isometric front view of a double hung head extrusion for windows showing my new design.

FIG. 2 is a top view of the double hung head extrusion for windows of FIG. 1.

FIG. 3 is a bottom view of the double hung head extrusion for windows of FIG. 1.

FIG. 4 is a front view of the double hung head extrusion for windows of FIG. 1.

FIG. 5 is a rear view of the double hung head extrusion for windows of FIG. 1.

FIG. 6 is a left side view of the double hung head extrusion for windows of FIG. 1; and,

FIG. 7 is a right side view of the double hung head extrusion for windows of FIG. 1.

The double hung head extrusion for windows is shown with a symbolic break in its length. The appearance of any portion of the double hung head extrusion for windows between the dash-dot break lines forms no part of the claimed design.
